UNITED STATES PATENT OFFICE.

KIICHIRO TOYODA, OF NAGOYA, JAPAN.

BUFFER FOR THE PICKING ARMS IN WEAVING LOOMS.

Application filed August 23, 1926. Serial No. 180,908.

My invention relates to a buffer for the picking arm in a weaving loom. The object of the invention is to attain a soft movement of the picking arm by a provision of a simple device which is adapted to destroy the momentum of the picking arm after it is operated. The device consists of a pair of the seatings and the pressing plates which are mounted on the slay and oppositely arranged across the passage for the picking arm, a strap having a passage for the picking arm and interposed between said seatings and pressing plates, said strap being adapted to be slid under friction, and a spring acting on the pressing plates for increasing the friction on the strap to restrain the sliding movement of the latter.

In the accompanying drawings in which one embodiment of the invention is shown by way of example:

Figure 1 is a front view of the device according to this invention,

Figure 2 is a sectional elevation thereof,

Figure 3 is a front view of the check strap, and

Figure 4 is a plan thereof.

The slay 1 is slotted forming a passage 2 for the picking arm A. On the under side of the slay 1 are secured two seatings 3 arranged oppositely across the passage slit 2. Anchored at the middle point each seating 3 has a screw bolt 4, by which a pressing plate 5 is mounted on each seating. A check strap 6 is interposed between the seatings 3 and the pressing plates 5, which strap has a central slit 7 forming a passage for the picking arm A. The strap 6 is also provided with two oblong guide slots 8. Thus, the parts are so arranged that the strap 6 is adapted to slide to and fro guided between the seatings 3 and the pressing plates 5. Preferably, the surface of each of the seatings 3 and pressing plates 5 in frictional contact with the strap 6 is shaped to conform to an arc of a circle, as shown in Figure 1.

In order to maintain the strap 6 in fric-

tional contact with the seatings 3 and the pressing plates, a spring 9 is mounted on each of the pressing plates 5, which spring 9 is held under a desired tension by a nut 10. It is obvious that the tension of the spring 9 may be adjusted at will by the nut 10.

At each end of the strap 6, there are attached two check tongues 11 and 12, one 55 being diverged upwardly and the other diverged downwardly, which tongues are adapted to engage with the picking arm A.

The operation of the invention is briefly as follows:—When the shuttle is thrown 60 into the shuttle box on one side by a picking action on the other side, the picking arm A will come into engagement with the check tongues 11 and 12, whereby the strap 6 will be moved outwardly. This movement is 65 however restrained by the increased friction between the strap 6 and the seatings 3 and between the former and the pressing plate 5, so that the momentum of the picking arm A will be destroyed by the strap 6. 70 Thus, it will be seen that, according to this invention, a soft movement of the picking arm may be attained by the provision of the buffer composed of the sliding strap 6.

What I claim is:—

1. In combination with the slay of a loom and the picking arm, a buffer comprising seatings secured to the underside of said slay, pressing plates, means connecting said pressing plates to said seatings, a strap having a slot for said picking arm and frictionally held between said seatings and said pressing plates, a spring acting on said pressing plates for maintaining said strap in frictional engagement with said seatings and 80 said pressing plates, and oppositely diverging check-tongues provided on said strap at each end of the slot therein.

2. The combination as specified in claim 1, in which said strap is provided with guide 90 slots engaging said connecting means.

In testimony whereof I affix my signature.

KIICHIRO TOYODA.
